Goldstein & Fox PLLC.(57) **CLAIM**

The ornamental design for a tire, as shown and described.

DESCRIPTION

FIG. 1 is a front perspective view of a tire showing the claimed design;

FIG. 2 is a front view thereof, the rear view being the same;
FIG. 3 is a top plan view thereof, the bottom plan view being the same;

FIG. 4 is a right side view thereof, the left side view being the same;

FIG. 5 is an enlarged view taken along the line 5-5 in FIG. 1;

FIG. 6 is an enlarged view of the portion between 6-6 and 6'-6' in FIG. 2; and,

FIG. 7 is a cross-sectional view taken along line 7-7 in FIG. 6.

In the drawings, the broken lines show portions of the tire that form no part of the claimed design. The broken lines immediately adjacent to the sidewall features shown in solid lines represent the boundary of the claim and form no part thereof.
